[57] CLAIM

The ornamental design for a sticker removal tool, as shown and described.

DESCRIPTION

FIG. 1 is top perspective view of a sticker removal tool showing our new design;

FIG. 2 is a bottom perspective view thereof;

FIG. 3 is a top plan view thereof;

FIG. 4 is a side elevational view taken from the right side of FIG. 1;

FIG. 5 is a bottom plan view thereof;

FIG. 6 is a front elevational view thereof;

FIG. 7 is a rear elevational view thereof; and,

FIG. 8 is a perspective view thereof, as operated to remove a sticker.

Any broken line illustrations in the drawing disclosure is not part of the design sought to be patented.
